UNITED STATES PATENT OFFICE.

EDWARD L. DAVIS, OF SCHENECTADY, NEW YORK

CONCRETE MOLD.

Application filed April 25, 1921. Serial No. 464,208.

To all whom it may concern:

Be it known that I, EDWARD L. DAVIS, a citizen of the United States, residing at Schenectady, in the county of Schenectady 5 and State of New York, have invented certain new and useful Improvements in Concrete Molds, of which the following is a specification.

This invention relates to improvements in 10 concrete molds and has for its object to provide an extensible mold.

Another object of the invention is to provide a mold for building concrete structures so arranged that the mold may be quickly 15 moved from place to place as the building of the structure proceeds.

Another object of the invention is to provide a concrete mold arranged to form a block upon a structure being built and means 20 whereby the mold may be removed leaving the block in its permanent position in the structure.

Another object of the invention is to provide an adjustable mold by means of which 25 sections of concrete may be molded upon the structure being built and the position of the mold quickly changed upon the structure.

With the above and other objects in view, I have invented a device illustrated in the 30 accompanying drawings in which—

Figure 1 is an elevational view of my improved mold,

Figure 2 is a side elevational view thereof, and

Figure 3 is a section on line 3—3 Figure 1.

This invention contemplates the provision of a mold for use in the building of concrete structures and is so formed that the concrete is molded in its permanent place 40 in a wall in the process of construction, whereby the wall may be continuously erected by horizontally shifting the mold immediately to a new position after each molded section has been formed until a complete concrete course has been finished, after 45 which the mold is raised to another similar course to be formed upon the course just completed.

In the following specification and in the 50 views in the drawings like reference characters indicate like parts and 1 indicates a concrete structure being formed by means of my improved mold 2, said mold being formed by a pair of longitudinal horizont- 55 tally disposed spaced apart wall members 3 and 4 to which are connected a plurality

of arms 5 and 6, respectively, said arms each being in the form of a bell crank, the vertical portions 7 and 8 of which extend above the upper edges 9 and 10 of the members 3 and 60 4 and have pivoted thereto the heads 11 and 12 of the right and left screws 13 and 14 which operate in the turn buckle members 15. The inclined upper ends 16 and 17 are pivoted to the outer ends of links 18 and 19, the inner ends of which are pivoted to the heads 20 and 21 of the right and left screws 22 and 23 operating in the turn buckle members 24 which also serve as operating handles by means of which the mold 70 is released from its operative position upon the concrete course 25 as the mold is vertically lifted from said course. It will readily be seen that upon raising up of the handles 24, the links 18 and 19 are drawn toward one another causing the drawing in of the extensions 16 and 17 of said arms 5 and 6 causing a pivotal action of said arms upon the pivot bolts 26 and 27 which throws the lower portion of said arms outwardly from said course 25 automatically as the mold is lifted. Secured to the members 15 by means of the swivel 28 are straps 29 to which are secured a central core 30 which forms the space 31 between the walls 32 and 33 of said structure 75 25. This core 30 is slightly less in height than the plates 3 and 4 in order that when adjusting the mold to a new position the core may be seated upon the tie plates 34, whereby the mold is rested in position 90 after which the handles 24 are forced down to a horizontal position causing the wall plates 3 and 4, which project at their lower ends slightly below the upper edge 35 of the former course, to adjust and lock themselves in vertical alignment with said former course. The operation of the said turn buckle handles 24 and their link connections with the upper ends 16 and 17 of the arms 5 and 6 is limited 95 in its downward movement by the studs 36 and 37, which limitation tends to lock the mold in its proper position and cause it to align vertically with the adjoining portion of the structure which has already been molded. The studs 36—37 and 38—39 are 100 placed so as to cause the horizontal center lines of the pivot bolts 26 and 27 in the turn buckle members 15 and the links 18 and 19 in the turn buckle members 24 to be slightly above the center lines of the said turn buckle members 24 and 15 when the turn buckle handles 24 are forced down to the limit in 105 110

the act of closing, there securely locking the mold. Should the horizontal center lines of the said pivots and the said turn buckle members coincide as to levels when the mold 5 is closed it would not be locked and would open with pressure exerted against the inner faces of the side plates 3 and 4. Locating the said studs in the manner described will prevent the deposited concrete from 10 prematurely opening the mold. The member 30 is slightly wedge shaped in order to facilitate its withdrawal from the concrete mass last molded.

In a short mold only two sets of the arms 15 4 and 5 are required, one set adjacent each end of the wall plates 3 and 4. However, in a longer mold, more of these arms and their connections will be necessary to stiffen the mold to prevent any tendency of the 20 plastic concrete causing said plates to bulge. The core 30 may be centrally located on the member 15 or it may be located toward one or the other sides of the molds according to where it is desired to have the wall sections 25 32 and 33 of different widths. It is obvious that if a solid wall is required the core 30 may be removed from the mold.

The arrangement of the turnbuckles 15 and 24 is such that the mould may be readily adjusted to its narrowest, its widest or to any desired intermediate thickness for the wall to be built.

I am aware that prior to my invention 35 concrete molds having cores for making hollow walls and with side plates that operate either horizontally or radially have been made. I therefore do not claim such a combination broadly; but

Having described my invention, that 40 which I claim as new and desire to procure by Letters Patent is:

1. A mold for concrete consisting of a set of frame elements with side plates attached thereto, upper and intermediate cross bar 15 members, a central core fractionally less in height than the said side plates pendent from the intermediate cross bar members, links pivotally connecting the upper cross bar members with the uppermost ends of the 20 said frame elements, whereby depressing the upper cross bar members, when the mold is resting free upon the said central core, closes and locks the mold in a predetermined position.

55 2. A mold for concrete comprising two or more sets of bell crank arms with side plates attached thereto, means whereby said plates may be relatively adjusted, consisting of two turn buckle members, the upper ones connected by links to the upper extremity of the said bell crank arms and the

intermediate ones pivotally connected to the same elements, whereby raising the upper turn buckle members opens the mold and releases the side plates from the molded 65 mass.

3. A mold for concrete comprising a plurality of bell crank arm frames with side plates attached thereto and a central core somewhat less in height than the said side 70 plates, means for adjusting said members relative to each other, said means consisting of two turn buckle members in said arm frames, one above the other, the lower, intermediate ones acting as ties, whereby a 75 downward movement of the upper turn buckle members, when the mold is sustained solely by the said central core, forces and locks the mold into place by a toggle action.

4. In a mold for concrete, the combination of sets of side arms with side plates attached thereto, overhead turn buckle members with pivotally connected side links jointed to the upper extremity of the said side arms, intermediate turn buckle members pivotally connected to the said side arms whereby the relative distance between the said side plates may be increased or diminished, means for locking the said mold when closed, said means consisting of a set 90 of studs so located in the said side arms that they limit the downward movement of the said turn buckle members when the center lines of the said turn buckle members are fractionally below the center lines of the 95 bearings in the said side arms.

5. A mold including molding boards equipped with uprights extending beyond the upper margins of said boards, a sectional cross bar the ends of which are pivotally connected to the upper ends of the said uprights, and a turnbuckle interposed between certain of said sections for relatively moving the upper ends of the said uprights. 100

6. A mold including molding boards 105 equipped with uprights extending beyond the upper margins of said boards, a sectional cross bar the ends of which are pivotally connected to the upper ends of the said uprights, and a turnbuckle interposed between certain of said sections for relatively moving the upper ends of the said uprights, whereby, in connection with adjusting the intermediate turnbuckle members, the perpendicularity and parallelism of the said 110 molding boards are secured.

In testimony whereof I affix my signature in the presence of two witnesses.

EDWARD L. DAVIS.
